UNITED STATES PATENT OFFICE.

GILBERT RIGG, OF MELBOURNE, VICTORIA, AND WILLIAM J. McBRIDE, OF BROKEN HILL, NEW SOUTH WALES, AUSTRALIA.

PROCESS OF AND APPARATUS FOR USE IN DRYING ORES, CONCENTRATES, AND OTHER GRANULAR MATERIALS.

Application filed July 11, 1922. Serial No. 574,218.

To all whom it may concern:

Be it known that GILBERT RIGG, of care of The Broken Hill Associated Smelters Proprietary Limited, of Collins House, 5 360-366 Collins Street, Melbourne, in the State of Victoria, and WILLIAM JOHN McBRIDE, of care of The Broken Hill South Limited, of Broken Hill, in the State of New South Wales, both in the Commonwealth of Australia, metallurgists, have invented certain new and useful Improvements in Processes of and Apparatus for Use in Drying Ores, Concentrates, and Other Granular Materials; and we do hereby 10 declare the following to be a full, clear, and exact description of the invention, such as will enable others skilled in the art to which it appertains to make and use the same.

This invention relates to a process of and 20 apparatus for use in drying ores, concentrates, and other granular materials, and refers more especially to processes wherein a hot blast or draught of heated air, or of a mixture of air and hot gases is employed to 25 carry off moisture from the materials being dried.

The invention may be employed for drying or dehydrating different kinds of 30 granular material and throughout the following specification, wherever the term "ores" is used it is to be understood as meaning and including other granular materials.

The object of the invention is to provide 35 means whereby granular material in a damp form can be efficiently and expeditiously dried or dehydrated in an economical and convenient manner.

We accomplish the object of this invention by providing a process of drying ores 40 which consists of forming a layer of the wet or damp material on a porous bed, drawing or forcing hot gases through the said layer and porous bed, drawing off the moisture with the hot gases, and finally drawing the 45 dried or dehydrated material through the said porous bed.

In practice, we provide a layer of the material to be dried, supported or imposed on a porous bed through which hot gases

are drawn. The bed is of such a nature 50 that the ore is retained on its surface while damp, but passes through it readily when dry. The interstices of the said porous bed are such as to offer a certain resistance to the passage of the gases, thus assisting to 55 maintain even conditions of draught through the bed.

The process may be operated continuously or intermittently. When operating continuously, the ore may be caused to progress 60 on a perforated bed.

The apparatus for giving effect to this invention may partake of a number of different modifications and briefly comprises a porous bed in communication with a chamber connected to an exhaust fan or blower. This porous bed is formed of a screen on the upper surface of which, or between two layers thereof is provided a layer of spherical or rounded bodies of a dimension which 65 will afford interstices through which the ore will pass more or less freely when dry. Means are provided for directing heated air or gas to the space adjacent to the porous bed and for intermittently or continuously 70 supplying damp ore to the bed and for stirring or agitating the ore to facilitate drying.

In order that this invention may be the better understood, we will now proceed to describe the same by reference to the accompanying sheets of drawings in which the different applications of this invention are 75 illustrated.

Figure 1 is a longitudinal section of one type of apparatus giving effect to this 80 invention.

Figure 2 is a transverse sectional elevation of Fig. 1.

Figure 3 is a detailed sectional view of the 85 perforated bed.

Figure 4 is a vertical section of a modified form of the apparatus for giving effect to this invention.

Figure 5 is a detailed sectional view of the 90 perforated bed used in Figure 4.

Figure 6 is a vertical section of another modified form of apparatus for giving effect to this invention.

In Figure 1 we have illustrated an apparatus in which the perforated bed is horizontal. The apparatus consists of a chamber A having a fire box B arranged at one end 5 with a communicating flue B' for delivering hot air and gases into the top of the chamber A. Extending longitudinally along the chamber A is a perforated screen C above which is adapted to move a series of 10 push conveyors D. These conveyors D are adapted to move the damp or wet ore which is fed on to the screen C through the chute E intermittently forward so that an even layer of the said damp ore is spread over 15 the screen C. This screen C is formed of perforated metal or woven wire and upon its surface is provided a bed of rounded balls, pebbles, or other coarse material. This perforated bed is shown more particularly 20 in Figure 3 consisting of the perforated metal screen C upon which is superimposed pebbles or balls C' upon which the layer of ore is imposed.

This layer of spherical or rounded bodies 25 may be balls of burnt clay, rounded silica grains or other pebbles, iron balls or other suitable materials for the purpose of forming a porous bed for the ore. It is essential that the balls, pebbles or other material employed for forming this bed have such dimensions and shape that interstices are provided through which the dried ore can pass. This layer of spherical or rounded bodies having a certain amount of mobility or 30 restricted movement, any tendency to choke or clog is avoided.

In the case of ore concentrates adapted to 35 pass through 40 mesh screen, we have found that balls or pebbles ranging from one-eighth of an inch to one quarter of an inch diameter and forming a layer of about one inch in thickness will well answer the purpose. The screen must be coarse enough to allow the dried ore particles to pass through, and fine enough to retain the balls, pebbles 40 or the like.

Beneath the screen C the chamber A is formed into a receiving box A' for the dried ore formed with an inclined back plate A² 45 whereby the material is delivered into the discharge chutes F. These chutes F are provided with control gates or doors F'. Leading from this lower portion A' of the chamber A is an exhaust G which is in communication with a fan or blower or other draught inducing means, whereby a continuous suction is maintained through the perforated bed drawing the hot gases down there-through. At the rear end of the chamber 50 A, a discharge chute H (having a control door H') is provided leading from that portion of the chamber above the perforated bed whereby any lumps or coarse material which do not pass through the perforated bed are withdrawn.

In practice, the ore is fed down continuously on to the perforated bed, and is conveyed therealong by means of the push conveyors D; at the same time, a current of hot dry air and gases is directed from the furnace B through the flue B' into the space of the chamber A above the surface of the layer of damp ore. 70

As a certain proportion of the moisture is removed, the particles of ore tend to adhere 75 together to a lesser degree and to trickle through the interstices of the perforated bed, the removal of the moisture is thus accelerated by the movement of an increased quantity of hot air and gases through the 80 said bed. Any tendency to choke or clog is avoided by the restricted movement of the balls, pebbles and the like of which the bed is composed. The dried ore is drawn through the perforated bed into the chamber 85 below, from whence it may be withdrawn from time to time through the chutes F.

Any dust which passes over through the exhaust G into the fan or blower is subsequently caught in a suitable dust collector. 90

When treating some material such as fine concentrates, care must be taken to avoid placing too deep a layer on the porous bed, as otherwise the moisture from the upper layers will be carried down and condensed 95 on the lower layers so as to interfere with the porosity of the bed and the satisfactory induction of the air and hot gases there-through which is essential to the working of the process. 100

In the apparatus illustrated in Figures 4 and 5, the perforated bed is in the form of a quasi-cylindrical screen preferably slightly tapering to form a truncated cone. Referring to these figures, A is an enclosed 105 chamber within which rotates a screen C^x mounted upon a central shaft K. This central shaft K carries a series of radial arms K' which support the screen C^x which is preferably formed as shown in Figure 5, 110 that is to say, comprising an inner perforated screen C^s and an outer perforated screen C^o, the space between accommodating pebbles, balls or other like rounded material C' between the interstices of which the dried material is caused to pass. The chamber A is formed with an extension A³ into 115 which delivers a flue B' leading from a furnace or other source of hot air and gases. Within this extension A³ is an internal sleeve J into which the ore is fed by the chute E from the conveyor belt E' (or other source of supply) to which a hood E² is attached for excluding the draught. A screw conveyor J' delivers the damp or wet ore 120 into the interior of the screen C^x. The other end of the chamber A is formed with a diaphragm through which the end of the screen C^x projects, more or less dividing the chamber A into two parts so that the fine 125

dried material passing through the screen is delivered into the portion A' from which it is withdrawn, whilst any lumps or coarse material which do not pass through the screen are delivered through the chute H.

The chamber A is in communication with a fan, blower or other exhausting device through the opening G.

In practice, the damp or wet ore is fed down through the chute E from the conveyor E' into the internal cylinder J where it is conveyed by the screw feed J' into the interior of the rotating screen C*. The wet ore is thrown out in a layer upon the inside of the screen C*. The radial arms K' on the shaft K serve to agitate and break up any lumps and evenly distribute the said ore upon the said screen.

The hot air and gases coming in through the flue B are delivered on the surface of the layer of ore and drawn through the screen to the exhaust outlet G. As the screen rotates, the balls, pebbles or the like of which the porous bed is composed are subject to a certain amount of restricted movement, thus avoiding any tendency to choke or clog. As the moisture is removed and the material becomes dried, it is carried through the screens and between the interstices of the balls, pebbles or other like material between the screens C² and C⁸.

The dried ore settles down into the lower portion A' of the chamber A and may be withdrawn from time to time, whilst any oversize or coarse lumps or foreign matter which will not pass through the screen are withdrawn through the chute H.

Referring to Figure 6, the chamber A is provided with a horizontal screen C which is formed as illustrated in Fig. 1, that is to say, with a layer of pebbles, balls and such like material on the surface thereof. Surrounding this screen C is an annular chamber L communicating with the chamber A above the surface of the screen C through the ports L'. The chamber A above the screen C is provided with a horizontal diaphragm A⁵. Above the screen C is mounted a vertical shaft M having a series of rotating blades or rabbles D' mounted upon arms D².

Above the chamber A is a feed chute E into which the ore is delivered from the conveyor E' and within the lower portion of the chamber A is provided an exhaust pipe G communicating with a fan, blower or other exhausting device. The draw-off F for the ore is arranged at the bottom of the chamber A' and a similar draw-off H for the coarser material or lumps which do not pass through the screen C. The operation of this machine is the same as that already described with regard to the other views.

We claim:

1. A process for drying ores and other

granular materials consisting of forming a layer of the material on a porous bed, inducing a current of hot gases through the said layer and porous bed, drawing off the moisture with the hot gases, and drawing the dried or dehydrated material through the said porous bed.

2. A process for drying ores and other granular materials consisting of forming a layer of the material on a porous bed, inducing a current of hot gases through the said layer and porous bed, agitating or stirring the layer of material on the said porous bed, drawing off the moisture with the hot gases, and drawing the dried or dehydrated material through the said porous bed.

3. A process for drying ores and other granular materials consisting of forming a layer of the material on a porous bed, inducing a current of hot gases through the said layer and porous bed, causing the said material to progress along the surface of the said porous bed, drawing off the moisture with the hot gases, and drawing the dried or dehydrated material through the said porous bed.

4. An apparatus for drying ores and other granular materials, consisting of a porous bed upon which a layer of the wet or damp material is imposed and through which hot gases are drawn, characterized by the fact that the bed is of such a nature that the ore is retained upon its surface whilst damp but passes through it when dried or dehydrated.

5. An apparatus for drying ores and other granular materials wherein a layer of the damp or wet material is imposed upon the surface of the porous bed through which hot gases are drawn, characterized by the fact that the said bed is formed of at least one perforated screen and a layer of pebbles, balls or other rounded materials, the interstices between which are such as to offer certain resistance to the passage of the gases and retaining the ore on the screen whilst still damp, but permitting of the passage of the ore therethrough when dried or dehydrated.

6. Apparatus for drying ores and other granular materials consisting of a chamber having a rotating screen mounted therein, means for feeding the wet or damp material into the interior of the said screen, means for supplying hot gases into the interior of the said screen and means for drawing off through the said screen the said hot gases, and means for withdrawing the dried ore from the chamber passing through the said perforated screen.

7. Apparatus for drying ores and other granular materials comprising a chamber having a rotating screen mounted therein, the wet or damp material being fed into the

interior of the said screen and hot gas being drawn through the said screen, characterized by the fact that the said rotating screen consists of an inner screen and an outer screen the space between which is filled with balls, pebbles, or other rounded materials the interstices between which are such as that

damp or wet material is retained on the screen whilst dry material is permitted to pass therethrough.

In testimony that we claim the foregoing as our invention, we have signed our names.

GILBERT RIGG.
WM. J. McBRIDE.
